UNITED STATES PATENT OFFICE.

WILLIAM H. ELLINGER, OF WICHITA FALLS, TEXAS.

WELL-DRILL WRENCH.

1,397,044.

Specification of Letters Patent.

Patented Nov. 15, 1921.

Application filed May 4, 1920. Serial No. 378,832.

To all whom it may concern:

Be it known that I, WILLIAM H. ELLINGER, a citizen of the United States, residing at Wichita Falls, in the county of 5 Wichita, State of Texas, have invented certain new and useful Improvements in Well-Drill Wrenches; and I do hereby declare the following to be a full, clear, and exact description of the invention, such as will 10 enable others skilled in the art to which it appertains to make and use the same.

This invention relates to new and useful improvements in well drill wrenches and is an improvement over my Patent 1,327,379, 15 issued Jan. 6, 1920.

In the structure of the former patent the rotatable member, when turned to screw or unscrew the drill bit, is not completely or properly supported, and it is one of the objects of the present invention to provide a 20 novel and improved means whereby the rotatable member will be supported during its complete rotation.

Also, in the prior structure, because of the 25 fact before stated, there was no anti-friction means between the rotatable member and the stationary member while the rotatable member was being rotated. It is a further object to provide a novel and improved anti-friction 30 means on which the rotatable member will be supported during its rotation.

A further object is to provide the member 35 on which the anti-friction means slides with a closure adapted to be opened when the wrench is to be engaged with the bit, and to be opened when the wrench is to be disengaged therefrom, the closure being a part of the support.

Other objects and advantages will be apparent from the following description when 40 taken in connection with the accompanying drawing.

In the drawing:

Figure 1 is a top plan view of the wrench 45 in position when engaged with a drill bit.

Fig. 2 is a top plan view of the wrench when being engaged or disengaged with respect to the bit, the closure being in open position.

50 Fig. 3 is a vertical longitudinal central sectional view through the head of the wrench on the line 3-3 of Fig. 1.

Fig. 4 is a horizontal sectional view on the line 4-4 of Fig. 3, just above the ball 55 retainer.

Referring particularly to the accompany-

ing drawing 10 represents a yoke having a handle 11, and a ring 12, the latter being used to attach a chain (not shown), whereby the wrench may be suspended at 60 the desired height for operation on the drill bit. Swiveled in the yoke is a segmental ring 13, the same being connected to the arms of the yoke by the screws or bolts 14, whereby the ring is permitted to swing. 65 Rotatable within the ring 13 is a ring 15 having an angular recess 16 formed through one side for the reception of the angular facet portion of a drill bit, said ring 15 having a lower peripheral flange 16' disposed horizontally under the ring 13, and a removable plate 17, secured to its upper face. This plate 17 has its peripheral edge portion projecting beyond the ring 15 over the ring 13, and in parallel relation to the flange 16'. 70

In the upper face of the ring 13 is formed a groove 18. Hinged to one end of the ring 13 at one side of the recess 16, is a member 13', which is arcuate and when swung over to engage its other end with the other end 80 of the ring 13, forms a continuation of the ring, at the same time closing or bridging the outer open end of the recess. In the upper face of this ring portion 13' is a groove 18' which forms a continuation of 85 the groove 18. A latch 19 is provided for securing the other end of the hinged member 13' to the other end of the ring 13.

Disposed between the projecting portion of the upper plate 17, and the upper face 90 of the ring 13, is a ring 20 having a portion cut out, as shown at 21, of a width equal to the width of the recess 16, and secured in this ring are the bearing balls 22, the upper portions of which bear against the lower 95 face of the projecting portion of the plate 17, and the lower portions of which run in the groove 18 of the ring 13, and in the groove 18' of the ring section 13', when said section is in closed and latched position.

Thus, when the handles 23, carried by the rotatable ring 13, are grasped and the ring rotated, the ball retainer, with the balls, will slide around with the ring and across 105 the bridging section 13', with the result that the rotatable ring 13 will be properly and antifrictionally supported at all times during its complete rotations, as when screwing or unscrewing the drill bit.

When the wrench is to be engaged with or disengaged from the drill bit, the section

13' is unlatched and swung to one side, after the ring 13 has been turned to register its recess with the opening of the yoke-carried ring 12.

5 What is claimed is:

In a well drill wrench, the combination with a yoke and an open ring swiveled in the yoke, of an open ring of substantially L-shaped cross section slidably supporting the first ring on the horizontal leg thereof, a removable notched plate carried by the vertical leg of the L-shaped ring and overlying the horizontal leg thereof, the notch of the plate registering with the opening of the ring, the lower face of the plate being formed with a ball race, an open ring sub-

stantially U-shaped in cross section disposed between the plate and the swiveled ring having antifriction bearings rotatably secured therein and running in the said race, 20 and a gate having a race in its upper face for movement of the bearings and movably connected to the first ring at one side of the opening thereof and detachably connected to the ring at the other side of the opening. 25

In testimony whereof, I affix my signature, in the presence of two witnesses.

WILLIAM H. ELLINGER.
